UNITED STATES PATENT OFFICE.

FRANK A. BELL AND JOHN F. LOVE, OF ENGLEWOOD, COLORADO.

JUNIOR TOILET SEAT.

Application filed May 14, 1928. Serial No. 277,609.

This invention relates to a toilet seat for children and has for its principal object the provision of a seat of this character which can be easily attached to any of the regular standard sized toilets.

Another object of the invention is to provide a junior toilet seat which while permanently attached to the toilet, may be quickly and easily folded out of the way when not in use.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views 20 of the drawing and throughout the description.

In the drawing:

Fig. 1 illustrates a perspective view of a toilet bowl with the invention in place thereon.

Fig. 2 is a detail view illustrating a method of constructing the arm rest hinges.

Fig. 3 is a detail view illustrating the method of attachment of the junior toilet seat 30 to the toilet bowl.

In the drawing, the toilet bowl is illustrated at 10, with its regular seat at 11, and lid at 12. In the standard construction the seat 11 and lid 12 are hinged on pedestals 13, 35 which are bolted through a flanged portion 14, cast on the toilet bowl 10. In attaching my invention to the bowl, I remove the pedestals 13 and place a supporting arm 15, beneath each of them as illustrated in Fig. 3, after 40 which the pedestals 13 are bolted back into position.

To each of the supporting arms 15, a bracket 16 is universally hinged at 17. One extremity of each of the brackets 16 is turned upwardly to provide a front arm rest standard 18. A rear arm rest standard 19 is welded or otherwise secured to the bracket 16.

The seat proper comprises two half sections 20 and 21, each being secured by means 50 of rivets 22, or in any other desired manner, to one of the brackets 16. The two seat sections 20 and 21 meet on a longitudinal medial line through the seat proper so that each section contains one-half of the usual toilet seat opening 30.

When the two sections, 20 and 21, are

brought together over the regular seat 11, they are secured in place by means of any desired latch 23, which in locking the two sections together prevents any sideward movement of the complete junior seat.

Arm rests 24 are hinged at their extremities to the arm rest standards 18 and 19, as indicated at 25. These hinges may be of any desired construction which will allow the 65 arm rests to fold inwardly upon the seat portions 20 and 21 and prevent them from being forced outwardly.

One method of forming the hinge joints 25, is illustrated in Fig. 2, in which an indented ring 26, is formed on the standards 18 and 19. The extremities of the arm rests 24 are turned inwardly to engage in these rings. The inherent resiliency of the arm rest forces it into the indentations in the rings 26 and 75 maintains the rest in the vertical position. They can, however, be easily folded downwardly on the seat when desired.

Suitable openings 28 are formed in the arm rests for the attachment of a restraining strap 80 29 for tying the child upon the seat.

When not in use the seat can be lifted and the latch 23 released. The two sections can then be swung around to the rear of the toilet bowl where they will be out of the way and 85 inconspicuous.

While a specific form of the improvement has been described and illustrated herein, it is desired to be understood that the same may be varied, within the scope of the appended 90 claims, without departing from the spirit of the invention.

Having thus described the invention, what we claim and desire to secure by Letters Patent is:

1. A junior toilet seat comprising supporting arms adapted to be attached by means of the hinge pedestals of a toilet bowl; brackets hinged to said supporting arms and a seat carried by said brackets.

2. A junior toilet seat comprising supporting arms adapted to be attached by means of the hinge pedestals of a toilet bowl; brackets hinged to said supporting arms and a seat carried by said brackets; said seat being formed 105 in two sections, each section being secured to one of said brackets.

3. A junior toilet seat comprising supporting arms adapted to be attached to a toilet bowl by means of the hinge pedestals thereof; 110 brackets hinged to said supporting arms; a seat carried by said brackets, said seat being

formed in two sections, each section being secured to one of said brackets; and means for locking said two sections together when in place.

5 4. A junior toilet seat comprising supporting arms adapted to be attached to a toilet bowl; brackets hinged to said supporting arms; a seat carried by said brackets, said seat being formed in two sections, each section being secured to one of said brackets; means for locking said two sections together when in place; and an arm rest carried by each of said brackets.

15 5. A junior toilet seat comprising supporting arms adapted to be attached to a toilet bowl by means of the hinge pedestals thereof; brackets hinged to said supporting arms; a seat carried by said brackets, said seat being formed in two sections, each section being secured to one of said brackets; means for locking said two sections together when in place; and an arm rest carried by each of said brackets, said arm rests being hinged so that they may be folded upon said seat sections.

20 25 6. A junior toilet seat comprising supporting arms adapted to be attached to a toilet bowl; brackets hinged to said supporting

arms; a seat carried by said brackets, said seat being formed in two sections, each section being secured to one of said brackets; means for locking said two sections together when in place; and an arm rest carried by each of said brackets, said arm rests being hinged so that they may be folded upon said seat sections, the hinge between said brackets and said supporting arms allowing universal movement of said brackets so that said seat sections may be swung downwardly and to the rear of said toilet bowl.

7. A junior toilet seat comprising supporting arms adapted to be attached to a toilet bowl; brackets hinged to said supporting arms and a seat carried by said brackets, said seat being formed in two sections, each section being secured to one of said brackets; and means for locking said two sections together when in place; an arm rest carried by each of said brackets; and means on said arm rests for attaching a restraining strap.

In testimony whereof, we affix our signatures.

FRANK A. BELL.
JOHN F. LOVE.
